UNITED STATES PATENT OFFICE.

JOHN TRISCHAN, OF CHICAGO, ILLINOIS.

RUBBER HEEL.

1,106,753.

Specification of Letters Patent. Patented Aug. 11, 1914.

Application filed March 7, 1914. Serial No. 823,249.

To all whom it may concern:

Be it known that I, JOHN TRISCHAN, a subject of the Emperor of Austria-Hungary, residing in the city of Chicago, county 5 of Cook, and State of Illinois, have invented certain new and useful Improvements in Rubber Heels, of which the following is a specification.

The object of my invention is to provide 10 rubber heels of superior durability, considering the quantity of rubber used, and means for fastening rubber heels to shoes which are both simple and effective, by which an accurate fit is more readily secured than by the 15 means now in use, and which obviate the driving of nails through the rubber heels.

In the drawings Figure 1 is a bottom plan view of one of my rubber heels; Fig. 2 is a top plan view of one of my rubber heels; 20 Fig. 3 is a partial sectional side elevation of a shoe, with my heel in position for marking the location of the nails by which it is to be held; Fig. 4 is an enlarged detail section of the fastening means, separated, in juxtaposition to each other; and Fig. 5 is a partly 25 sectional side view showing my heel in position.

Referring to the drawings, a rubber heel 10 is provided on its lower surface with half-spherical warts 11, and on its upper surface 30 with elongated central depression 12. Opposite to warts 11 there are embedded in heel 10, at its upper surface, preferably split metallic sockets 13, ring flanges 14 of which 35 lie flush with such upper surface while their pockets 15 are adjusted to receive and to hold rounded heads 16 of nails 17, which are driven into the heelbase 18 of shoe 19, and which are preferably provided with disk 40 flanges 20 which lie flush with the lower surface of base 18, limiting the penetration of nails 17 into base 18. Needle-openings 21 extend through the centers of warts 11 and

pockets 15 to permit of the insertion of a needle 22 for the purpose of marking on the 45 surface of base 18 the spots at which nails 16 are to be driven into such surface in order that they may be properly located with reference to sockets 13 around which rubber-heel 10 is cast, and which therefore cannot 50 be moved from their respective locations.

It will be observed that central depression 12 saves rubber, and at the same time tends to promote all around contact of the upper edges of heel 10 with the lower edges 55 of base 18, by obviating any contact of these bodies near the center; also that warts 11, make it convenient to locate openings 21 on the lower side of heel 10 for the purpose of inserting needle 22; and finally that my construction does away with the driving of 60 nails through the rubberheels.

I claim:

1. In rubberheels, the combination of, split, metallic sockets arranged to engage the 65 heads of nails driven into a heelbase, with a rubberheel cast around said sockets, said rubberheel and sockets having needle openings extending through the center of said sockets at right angles to the treading surface of said heel, for the purpose described. 70

2. In rubberheels, the combination of, split, metallic sockets, arranged to engage the heads of nails driven into a heelbase, with a rubberheel cast around said sockets, 75 having a semispherical wart on its treading surface directly below each of said sockets and a needle opening extending through the center of each socket and wart, at right angles to the treading surface of the heel, for 80 the purpose described.

JOHN TRISCHAN.
